UNITED STATES PATENT OFFICE.

SIDNEY O. BIGNEY, OF ATTLEBOROUGH, MASSACHUSETTS.

DESIGN FOR A CHAIN-LINK.

SPECIFICATION forming part of Design No. 32,618, dated May 1, 1900.

Application filed April 7, 1900. Serial No. 12,925. Term of patent 7 years.

To all whom it may concern:

Be it known that I, SIDNEY O. BIGNEY, a citizen of the United States, residing at Attleborough, in the county of Bristol and State of Massachusetts, have invented and produced a new and original Design for a Chain-Link, of which the following is a specification, reference being had to the accompanying drawings, forming part thereof.

Figure 1 is a side view of my newly-designed chain-link. Fig. 2 is a transverse sectional view of the link on the line A A of Fig. 1. Fig. 3 is a longitudinal sectional view of the link on the line B B of Fig. 1.

The leading feature of my design consists in the curved ornamented depression between the inner and outer beveled surfaces on each side of the link, whereby the planished beveled surfaces are separated, as will be more fully set forth hereinafter.

In the drawings, *aa* indicate the round ends of the link where when a chain is formed the links are secured together. The link is of oval shape, having the long curved sides

bb and the short bent ends *aa*. The long ²⁵ curved sides *bb* are of approximately diamond-shaped cross-section, as is shown in Fig. 2. Beveled and preferably planished surfaces *b'b'* on the outer parts of the curved sides *b* are separated from the inner beveled surfaces *b²b²* by the faceted or otherwise ornamented groove *b³*. The beveled surfaces *b'* and *b²* merge into the round section of the ends *aa*.

The link is designed for use in a cable, curb, ³⁵ or other chain.

Having described my invention, what I claim as new, and desire to secure by Letters Patent, is—

The design for a chain-link, as herein shown ⁴⁰ and described.

In testimony whereof I have signed my name to this specification in the presence of two subscribing witnesses.

SIDNEY O. BIGNEY.
